UNITED STATES PATENT OFFICE.

ALVIN V. ROWE, OF GALESBURG, ILLINOIS.

GATE.

1,388,375.

Specification of Letters Patent. Patented Aug. 23, 1921.

Application filed March 8, 1918, Serial No. 221,171. Renewed February 23, 1921. Serial No. 447,222.

To all whom it may concern:

Be it known that I, ALVIN V. ROWE, a citizen of the United States, residing at Galesburg, in the county of Knox and State of Illinois, have invented a new and useful Gate, of which the following is a specification.

My invention relates more particularly to that class of farm-gates which may be tilted upward at their free ends, in order to permit them to swing freely over accumulations of snow, mud, etc., to permit small stock to pass under the gate, while excluding larger stock, and for adjusting the gate to a horizontal position should it or its supporting post become sagged.

The principal object of the invention is to provide novel hinge-mechanism which acts also as a means of supporting or locking the gate in tilted position.

Another object is to provide means, acting conjointly with said hinge-mechanism, whereby the gate body may be elevated vertically, to a horizontal position.

The invention consists, substantially, in the improvements hereinafter described.

In the accompanying drawing:

Figure 1 is a front elevation of a gate in which my improvements are incorporated, the parts being shown as in normal position;

Fig. 2, a similar view, but the gate shown as tilted upwardly at its free end;

Fig. 3, a similar view, the gate shown as elevated bodily;

Fig. 4, an enlarged transverse section, taken in the line 4-4 in Fig. 1, the gripping member shown as released from and in position to be moved longitudinally on the hinge-bar;

Fig. 5, an enlarged longitudinal section, partly in elevation, the plane of section being in the line 5-5 in Fig. 4; and

Fig. 6, a top plan detail the position of which is indicated by the line 6-6 in Fig. 1.

Considering the drawings in detail and indicating each element by a numeral, 2 indicates a supporting post provided with gate hooks or pintles 3, 4 and 5 which may be of any suitable construction.

6 designates the gate-body, comprising longitudinally disposed slats 7 united by co-acting pairs of vertical standards 8 and inclined standards 9. I have shown each pair of standards as provided with co-acting slots 10.

The usual securing bolts 11 and nuts 12 pass through these slots and except in the top and bottom slats are disposed above and below the respective upper and lower edges thereof.

13 denotes a hinge bar, preferably formed of a length of channel iron bent upon itself at its midlength to form a pintle-engaging eye 14, the extended or body portions of the bar lying in opposition and provided with registering apertures 15, as shown best in Figs. 4 and 5.

16 indicates a supporting yoke and 17 a wear-preventive plate secured thereto preferably by a rivet 18. The branches of the yoke are bent horizontally outward as shown to form shoulders 19 each of which is provided with a bolt-receiving aperture 20 presently described, and their terminals 19' are bent thence downward, primarily in order to solidify and support the shoulders. The upstanding branches of a U-bolt 21 penetrate the apertures 20, and each is engaged by a nut 22. The opposed cheeks 23 of a slat-supporting yoke 25 are provided with registering apertures through which passes the cross-bar of the U-bolt, the lower edge of the upper gate-slat resting on the bed-plate of the yoke.

26 designates a gripping member the opposed cheeks 27 of which are provided with registering slots 28 which are engaged by the cross-bar of the U-bolt, the gripping member being thus slidably hung thereon but always in rear of its vertical central line, whereby the constant tendency of the forward edge of the gripping member is to swing downward. The front-plate 29 of the gripping member is provided with an opening 30 through which the hinge bar 13 is projected. The upper portion of said plate is cut away as at 31 whereby to provide tongues 32 and a detent shoulder 33. The cheeks 27 are provided with registering apertures 34 which are adapted for registration with the apertures 15 in the hinge bar 13, in order to permit the insertion of a locking-pin 36 whereby the gripping member may be locked in a predetermined position on said bar.

35 designates a gripping member releasing cord or wire secured at one end to an opening 36' in the lower end of the gripping member and at its other end to the free end of the gate. 37 designates a lower hinge-member of well known construction.

In operation, assume the parts to be in the

- relative positions shown in Fig. 1. It will be seen that the slat 7 is firmly gripped between the two yokes, but that it is not penetrated by any bolt or in other way weakened.
- 5 Also it will be seen that the gripping member is tilted slightly backward at its lower end, thus bringing the hinge bar out of alinement with the opening 30 and causing the upper and lower walls of the latter to
- 10 grip said rod. To tilt the gate to the position shown in Fig. 2, or to any greater or lesser angle within the limits of the hinge bar 13, the operator will simultaneously (or substantially so) very slightly raise the free
- 15 end of the gate and pull upon the string to release the gripping action of the upper and lower walls of the opening 30 from the bar 13, this being done by the gripping member so swinging that the bar will aline with said
- 20 opening. The operator will continue to raise the gate end until it has reached the desired position, whereupon, instantly upon his releasing the gate it will tend to fall and the gripping member will upon its release
- 25 automatically swing into tilted position with reference to the hinge bar, whereby to grip the latter and hold the gate in adjusted position. However, the gripping member will not be bearing on the U-bolt 21 nor vice
- 30 versa, for it is gripped upon the bar 13 and its shoulder 33 is bearing against the bed-plate of the yoke 25. Thus the gripping member will have no tendency to wear and cut into, to eventually weaken, the cross-bar of the U-bolt. It is to be noted that the gripping member is not pivoted upon said bolt, but that it is slidably mounted (by means of the slots 28) thereon, whereby it
- 35 is free to swing quite a distance off center and thus render its gravity-action much more rapid. The rear edges of the tongues 32 are adapted to slide over the front edge of the bed-plate of the yoke 25 and thus guide the shoulder 33 into position to strike
- 40 said plate. Should it be desired to permanently lock the gate in any of its adjusted positions it may be accomplished by inserting a pin or cotter through the registering apertures 15 and 34 in the bar 13 and gripping member respectively, in the ordinary manner.

Again assume the parts to be in the relative positions shown in Fig. 1. To bodily elevate the gate to the position shown in Fig. 55 3 the operator merely has to raise the lower hinge-member 37 off the pintle 5 and hang it upon the pintle 4, for the bar 13 will yield upwardly at its free end and the gripping member will move over it to the proper

60 position. Instantly upon the gate being released by the operator it will cause the gripping member to drop (by gravity) and the latter will automatically clutch or grip the rod 13 as above described.

65 A large portion of the stress comes upon

the upper edge of the top slat. In order to relieve this and to prevent serious mutilation thereof I provide the plate 17 which functions as a rest-plate-extension from the yoke 16 and distributing the bearing surface over 70 a much larger area than would said plate alone.

Having thus described my invention I claim as new the following, to-wit:

1. In a gate of the character described, a 75 gate-slat loop, an element coacting therewith to clasp the gate slat, a U-bolt engaged with one at least of said elements, a locking and releasing member engaging the U-bolt, and a hinge-bar which it is adapted to engage at selective points.

2. In a gate of the character described, a 80 gate-slat loop, an element coacting therewith to clasp the gate-slat, a U-bolt engaged with at least one of said elements, a locking and releasing member slidably mounted on the U-bolt, and a hinge-bar adapted for 85 selective engagements by the member.

3. In a gate of the character described and including a slat, means bearing on said slat, an element having a cross-bar, connected with said means, a locking and releasing member slidably connected with the last recited element, and a hinge-bar adapted for 90 selective engagements by the member. 95

4. In a gate of the character described and including a slat, an inverted U-shaped yoke resting on said slat, an inverted U-shaped yoke on which the slat rests, a U-bolt connecting them, a member connected with the 100 U-bolt, and a hinge-bar adapted for selective engagements by the member.

5. In a gate of the character described and including a slat, an element bearing on 105 said slat, an element on which the slat bears, means for connecting them, a member connected with the connecting means, and a hinge-bar adapted for selective engagements by the member.

6. In a gate of the character described 110 and including a slat, an element bearing on said slat, an element on which the slat bears, means for connecting them, a member slidably connected with the connecting means, and a hinge-bar adapted for selective 115 engagements by the member.

7. In a gate of the character described, a tilting gate including a slat, slat-clamping devices, a locking and releasing swinging member engaging opposite sides of the slot 120 connected off center with said devices and a hinge-bar adapted for selective engagements by the member.

8. In a gate of the character described, a tilting gate including a slat, slat-clamping 125 devices, engaging opposite sides of the slot, a hinge-bar supported at the inner end of the gate, and a gravity-actuated member adapted for selective engagements with said hinge-bar and carried by said devices. 130

9. In combination with a post, a tilting gate having a slat, means engaging the slat on opposite sides thereof, a movable element carried by the post, and means connected to said first means and engageable with said element at different points along the length thereof to hold the gate in position.

10. In a gate including a slat, devices substantially embracing opposite sides of but not penetrating said slat, a member connected with said devices, and a hinge-bar engaged by the member.

11. In a gate including a slat, a yoke crossing the top of the slat, an anti-mutilating element connected with said yoke and lying on top of the slat, and hinge-devices connected with said yoke.

12. In a gate including a slat, slat-engaging devices one of which includes a transversely arranged cross-bar, and a member having spaced cheeks provided with registering apertures through which said cross-bar passes, whereby to support the member, and a hinge-bar adapted for selective engagements by the member.

13. In a gate including a slat, slat-engaging devices one of which includes a transversely arranged cross-bar, and a mem-

ber having spaced cheeks provided with registering slots through which said cross-bar passes, whereby to support the member, and a hinge-bar adapted for selective engagements by the member.

14. In a gate, a slat-striding yoke having horizontally arranged apertured shoulders, a U-bolt passing upwardly through the apertures, a slat-supporting element pivotally mounted on the cross-bar of the U-bolt, a gripping and releasing element non-pivotally mounted on said cross-bar, and a hinge-bar adapted for engagement by the gripping and releasing element.

15. In combination with a post, a tilting gate having a slat, means engaging the upper and lower edges of said slat to grip same, a device movably connected to the post, means connected to said first means and engageable with said device at different points thereon to hold the gate in position, and means to adjustably and selectively set the second means at different points along the length of said device.

In testimony whereof I hereunto sign my name this 1st day of March, 1918, at Galesburg, Illinois.

ALVIN V. ROWE.
